DESIGN FOR A CAP FOR A BOTTLE OR SIMILAR CONTAINER

William M. Van Ostrom, Cranford, N. J.

Application May 26, 1939, Serial No. 85,217

Term of patent 7 years

To all whom it may concern:

Be it known that I, William M. Van Ostrom, a citizen of the United States, residing in Cranford, county of Union, State of New Jersey, have invented a new, original, and ornamental Design for a Cap for a Bottle or Similar Container, of which the following is a specification, reference being had to the accompanying drawing, forming part thereof.

Figure 1 is a view in elevation of a cap for a bottle or similar container, showing my new design;

Figure 2 is a top plan view of the same.

I claim:

The ornamental design for a cap for a bottle or similar container, as shown.

WILLIAM M. VAN OSTROM.
